UNITED STATES PATENT OFFICE.

JOSEPH B. DOCKERY AND JOSEPH GILMAN CHOUTEAU, OF ST. LOUIS,
MISSOURI.

DESIGN FOR A PIPE-SWAGE.

SPECIFICATION forming part of Design No. 25,127, dated February 4, 1896.

Application filed December 27, 1895. Serial No. 573,475. Term of patent 14 years.

To all whom it may concern:

Be it known that we, JOSEPH B. DOCKERY and JOSEPH GILMAN CHOUTEAU, of the city of St. Louis, State of Missouri, have invented 5 a new and original Design for a Pipe-Swage, of which the following is a full, clear, and exact description, reference being had to the accompanying drawing, forming a part hereof.

The drawing is a side elevation of a pipe- 10 swage embodying our design.

The leading feature of our design is a cylindrical body from which projects longitudinally a body of smaller and uniform diameter, the point of meeting between the smaller 15 and larger bodies being gradually curved, this forming between said bodies a concaved surface.

1 indicates the larger cylindrical body. Pro-

jecting centrally relative to the periphery of said cylindrical body 1 is a cylindrical body 20 2 of uniform diameter. The surface of the point where the bodies 1 and 2 merge into each other is gradually curved into a uniform concaved surface 3, while the end of the body 2 may be slightly convex, as indicated by 4. 25

We claim—

The design for a pipe-swage, as herein shown and described.

In testimony whereof we affix our signatures in presence of two witnesses.

JOSEPH B. DOCKERY.

JOSEPH GILMAN CHOUTEAU.

Witnesses:

E. E. LONGAN,
JOHN C. HIGDON.
